DRAFTSMAN'S INSTRUMENT

Jack V. Rich, Chicago, Ill.

Application July 23, 1936, Serial No. 92,110

2 Claims. (Cl. 33—93)

The invention relates to draftsmen's instruments or tools and more particularly it relates to instruments or tools combining the principles of a triangle, a protractor, and a plurality of graduated straight edges providing scales, certain of the straight edges having fixed relative angles of inclination and others being relatively rotatable to vary their relations to the other straight edges as desired.

10 One of the objects of the invention is the provision of improvements in instruments of the kind described, whereby such instruments are adapted for use as a thirty-sixty degree triangle, as a forty-five degree triangle and as a protractor, and also provides an arm which may be graduated to form a scale, if desired, the arm being rotatable about a pivot point and adapted to be fastened at any desired angle of inclination relative to the straight edges provided by the triangle, with the arm and triangle adapted to lie flat upon a drawing table or sheet of paper.

Another object of the invention is the provision of an improved combination draftsman's tool or instrument of the kind described which is durable, relatively inexpensive, simple in operation, and satisfactory for its intended purpose.

Many other objects and advantages of the instrument herein shown and described will be obvious to those skilled in the art from the description herein given.

To this end the invention consists in the novel combination and arrangement of parts herein shown and described and more particularly pointed out in the appended claims.

Referring now to the drawing,

Fig. 1 is a plan view of combination drawing instrument embodying the principles of the invention; and

Fig. 2 is an enlarged scale sectional view along the line 2—2 of Fig. 1.

Referring now more particularly to the drawing, the numeral 10 generally designates a generally triangular shaped plate number preferably consisting of celluloid or of any other suitable transparent material. The triangular member 10 is bounded by perpendicularly extending straight edges 11 and 12, the hypotenuse comprising two straight edges 13 and 14. The edge 13 is inclined to the edges 11 and 12 at angles of sixty and thirty degrees respectively, and the edge 14 is inclined to the edges 11 and 12 at an angle of forty-five degrees. The described bounding edges of the member 10 adapt it to be used as a thirty-sixty degree triangle and

also as a forty-five degree triangle. The member 10 is graduated adjacent its bounding edges to form scales, the graduations shown being in inches and fractions thereof and are typical only. One face of the triangular plate member 10 provides an arcuate quadrant vernier 15 graduated in both directions and on the inside of the vernier the plate member provides an arcuate slot 16.

An elongated member 17, preferably constructed of aluminum or similar light metal, is rotatable relative to the plate member 10. The member 17 comprises a pair of perpendicularly extending arms 18 and 19. The arm 18 is bounded by parallel straight edges and extends along the edge 12 of the plate member 10, the arm and plate member both being adapted to have their lower faces in contact with the drawing sheet or board. The arm 19 projects over the member 10 and is fastened to the latter by a pivot member 20 projecting through a metallic sleeve sleeve 24 carried by the member 10. The arm 19 is clamped between a head 22 and countersunk shoulder 23 formed on the pivot member 20. The lower end of the sleeve 24 is tapered to receive a countersink for the correspondingly tapered end of the pivot member 20. An annular metallic washer 25 provides a spacer between the plate member 10 and arm 19 adjacent the pivot member 20, the construction of the pivot member and of the sleeve 24 being such that the bearing parts are all metal and there is no wear on the material comprising the plate member 10.

The arm 19 overlaps the arm 18, the arms being rigidly connected by a plurality of rivets 26. The free end of the arm 19 has a central groove 27 forming a pointer and shown in alignment with one of the end graduations comprising the vernier 15, in which position the arm 18 extends along and coincides with the edge 12 of the member 10. The arms 18 and 19 are adapted to be fastened either in the full line position shown, or at any selected angle of inclination of the arm 18 relative to the edge 12, as shown in dotted lines, the selected angle being indicated by the reading of the pointer 27 on the vernier 15. The fastening means comprises a bolt 28 carried by the arm 19. The head of the bolt 28 is positioned in and movable along the lower enlarged portion of the slot 16. The other end of the bolt 28 is threaded to receive a knurled head or knob 29. A pair of washers 30 separate the arm 19 from the knob 29 and the plate member 10 respectively and serve thereby to re-enforce the plate member when the arm is clamped be-

tween the washers by manipulation of the knob. The knob 29 is loosened when it is desirable to change the angle of inclination of the arms 18 and 19 and is easily tightened to hold the arms 5 at any selected reading on the vernier 15.

The sleeve 24, the rivets 26, and the head of the bolt 28 are all countersunk as described in order that the lower face of the plate member 10 and of the arm 18 may be flush with the drawing board or sheet of paper. The described construction of the combination instrument provides novel means for drawing lines at the more frequent angles of inclination such as thirty, forty-five, sixty and ninety degrees, and combines, with 15 a triangle, providing straight edges having all of the suggested fixed relative angles of inclination, a rotatable straight edge and a protractor adapted to indicate any angle of inclination of the rotatable straight edge from zero to ninety 20 degrees.

Having thus described my invention it is obvious that various immaterial modifications may be made in the same without departing from the spirit of the invention; hence I do not wish to 25 be understood as limiting myself to the exact form, construction, arrangement and combination of features herein shown and described or uses mentioned.

I claim:

30 1. A drafting instrument of the kind described comprising a triangle body, an elongated member comprising a pair of arms angularly related to each other, one of said arms overlapping and the other extending along one edge of the triangle 35 body, a pivot extending through and connecting the overlapping arm with said body, said overlapping arm providing a groove or the like adapt-

ed as a pointer and the upper face of said body providing an arcuate scale for cooperation with the pointer, said pivot having its lower end countersunk within the body and the arm extending along one edge of the body having its lower face 5 in the same plane as the lower face of the body whereby rotation of the pointer along the arcuate scale correspondingly moves the other arm over the surface on which the triangle body is positioned. 10

2. A drafting instrument of the kind described comprising a triangle body, an elongated member comprising a pair of arms angularly related to each other, one of said arms overlapping and the other extending along one edge of the triangle body, a pivot extending through and connecting the overlapping arm with said body, said overlapping arm providing a pointer and the upper face of said body providing an arcuate scale for cooperation with the pointer, said pivot 15 having its lower end countersunk within the body and the arm extending along one edge of the body having its lower face in the same plane as the lower face of the body whereby rotation of the pointer along the arcuate scale correspondingly moves the other arm over the surface on which the triangle body is positioned, said body 20 providing an arcuate slot and arcuate extensions of the slot on its underside concentric with said pivot, a bolt positioned in the slot with its lower end providing a head movable within said extensions of the slot and its upper end connected with said overlapping arm, and means operable to clamp the bolt to said body to lock said arms against rotation at any selected reading of the 25 pointer on the arcuate scale. 30
